UNITED STATES PATENT OFFICE.

SAMUEL E. GUINN, OF JOHNSON CITY, TENNESSEE.

GASLIGHTER.

Application filed November 26, 1921, Serial No. 517,907. Renewed March 27, 1924.

To all whom it may concern:

Be it known that I, SAMUEL E. GUINN, a citizen of the United States, residing at Johnson City, in the county of Washington 5 and State of Tennessee, have invented certain new and useful Improvements in Gaslighters, of which the following is a specification.

This invention relates to an improvement in gas lighters of that type designed to be 10 connected to the gas supply pipe for gas ranges or the like, and to ignite gas passing thru the lighter at will thru the use of the usual pyrophoric material, the igniter being adapted to be held in the hand and 15 moved to any position for the ignition of a burner or the like on the range.

The use of a lighter of this type has been heretofore proposed and the present invention is directed particularly to materially 20 simplifying the construction of such types of gas lighters and to providing details of structure which in addition to their simplicity provide a construction capable of 25 withstanding hard usage while at the same time insuring the effective operation under all conditions.

The invention is illustrated in the accompanying drawings, in which:

Fig. 1 is a perspective view of the improved gas lighter.

Fig. 2 is a perspective view of the holder for the pyrophoric material.

Fig. 3 is a sectional view illustrating the means for securing the abrader for the 30 pyrophoric material in place.

Fig. 4 is a section on line 4—4 of Fig. 3.

The improved gas lighter comprises a flexible tube 1, having a valve structure 2 at one end whereby the lighter may be connected to the gas supply pipe of a gas stove or range, the valve structure herein shown being more particularly described later. The opposite end of the flexible tube 1 is connected with a rigid pipe-like extension 3, 40 on which is arranged a handle 4 for convenient manipulation of the device. The free end of the pipe 3 is provided with a rectangular casing, forming an ignition chamber, this casing being open at the end remote 45 from the pipe 3. The end of the pipe 3 at the juncture with the ignition chamber is closed by a disc of fire resisting material 5, formed with a fine opening therethru as 6, whereby the gas is delivered lengthwise 50 of the ignition chamber in a comparatively

fine stream. The abrader 7 is held within the ignition chamber and against one wall thereof in a manner permitting its convenient withdrawal when desired. To this end, the opposing walls of the chamber are 60 formed with elongated slots 8 of a size to receive the abrader 7, such as a file or the like, and one longitudinal edge of the abrader is formed with a recess 9. A set screw 10 is threaded thru the wall of the 65 casing to seat in said recess, so that the abrader is held against one wall of the casing in a manner to permit its convenient removal, as by withdrawal of the screw 10, the abrader is free to be removed. The wall 70 of the casing of the ignition chamber opposite the abrader is cut away or slotted at 11, the cut away portion extending into the top and bottom walls as shown. There is thus provided a recess to permit the operation of the holder for the pyrophoric material. This holder comprises a member 75 formed of intersecting rod-like sections 12 and 13, the former constituting the holder proper for the pyrophoric material and being hollow thruout its entire length. That end of the material holder proper remote from the abrader has its wall diametrically slotted as at 14, the slot extending thruout the full portion of the holder beyond the 80 rod section 13. The rod section 13 constitutes the means for connecting the holder to the spring element and manually operable element whereby the necessary action for the pyrophoric material is obtained. The spring 85 acting element for the holder includes a spring strip, preferably spring wire 15, secured at one end to the casing forming the ignition chamber, then extended longitudinally of the pipe 3 to a position adjacent 90 the forward end of the handle 4, then coiled about the pipe and projected forwardly, with the terminal secured in the free end of the rod-like section 13 of the holder. This arrangement tends to maintain the holder with the holder section proper 12, resting against the bottom of the ignition chamber. Any tendency to move the holder longitudinally of the face of the abrader tensions 95 the spring member to cause the holder to 100 return to its normal position.

The manual operating member for the holder comprises a lever-like element 16 pivotally supported at 17 on a screw threaded into an appropriate part of the ignition 110

chamber, the rear end of this lever terminating adjacent the handle 4 in a thumb piece 18. This lever in advance of its pivot as at 19 is turned laterally and fits more or less loosely in an opening in the upper end of the vertical rod-like member 13 of the holder.

The pyrophoric material 20 is placed loosely in the arm 12 of the holder proper and is automatically fed to proper position for action in conjunction with the abrader by a spring coiled about the spring wire 15 adjacent the connection of the latter by the holder proper, one terminal of this spring passing loosely thru the adjacent wall of the ignition chamber and the other terminal resting in the slot 14 formed in the holder proper. The latter spring terminal bears upon the pyrophoric material and maintains the same in proper position to be acted upon by the abrader, the spring automatically feeding the material as it is worn away.

The valve structure 2 comprises a section connected to the tube 1 and a second section 21 threaded thereon to permit comparatively free turning between limits of the lighter relative to the section 21 without interfering with the gas connection. Section 21 is formed for connection with the gas supply pipe and has a cut off 22 therein. A needle valve 23 controls the normal passage of the gas thru the valve section at will.

Obviously with the gas cut off open, gas will flow in a fine stream into and thru the ignition chamber. The holder is now actuated by the use of the hand operating lever and released, and the spring will draw the pyrophoric material rapidly over the abrading surface to produce a spark which will ignite the stream of gas passing thru the chamber and thereby furnish a flame which projects a considerable distance beyond the open end of the chamber, and which may of course be used for igniting the usual burners of the range or for other purposes.

Attention is particularly called to the fact that the various parts of the structure are readily separable. The abrader can be readily removed when replacement or repair is desired, the pyrophoric material is almost as conveniently removed, being readily withdrawn from the ignition chamber upon the separation of the manually operable lever; and furthermore the pyrophoric material in said holder is automatically fed to operative position with respect to the abrader, without necessitating manual adjustment of any part.

Claims:

1. A gas lighter including a gas pipe, an ignition casing arranged at one end thereof, a holder for pyrophoric material movable in but wholly free of engagement with said casing, and an abrading element for said material removably secured to one wall of said casing.

2. A gas lighter including a gas pipe, an ignition chamber into which the gas is delivered, a holder for pyrophoric material movable in said chamber, an abrading element having its ends normally seated in opposed slots in said chamber, thru either of which the element is movable, and a screw threaded into the wall of the chamber and engaging a recess in the edge of the element to removably secure the element in position. 70

3. A gas lighter including a gas pipe, an ignition casing at one end thereof, an abrading element arranged in said casing, a holder for pyrophoric material, a spring element connected remote from said casing and adapted to support the holder for movement in but free of contact with said casing, and a lever connected to the holder to move the same in the casing against the tension of the spring element. 80

4. A gas lighter including a gas pipe, an ignition casing at one end thereof, an abrading element removably secured in said casing, a holder for pyrophoric material movable in said casing, a spring arm connected to said holder, coiled about the pipe and secured to the casing, and a lever pivotally supported on the casing and having one end connected to the holder. 90

5. A gas lighter including a gas pipe, a rectangular ignition casing arranged at one end of the pipe, an abrading element mounted in the casing, and a spring operated holder for pyrophoric material movable in the casing, said holder including a tubular portion to receive the pyrophoric material formed with diametrically opposed slots, and a spring pressed arm movable in said slots, whereby to automatically feed the pyrophoric material to operative position in 105 the use of the lighter.

6. A gas lighter including a gas pipe, a rectangular ignition casing arranged at one end of the pipe, an abrading element mounted in the casing, a holder for pyrophoric material of the cross-arm form, one arm of which is tubular to receive the pyrophoric material, a spring strip secured to one end of the other of said arms extended beyond the casing, coiled about the pipe and terminally secured to the casing, and a spring member coiled about said strip adjacent the holder and having one terminal slidably mounted in an opening in the casing and the other terminal operating in diametrically opposed slots in the tubular arm of the holder. 110

7. A gas lighter including a gas pipe, a manually controlled valve arranged at one end thereof, a rectangular casing arranged at the opposite end of the pipe and open at the end remote from the pipe, said casing being formed in the upper and lower walls and thruout one side wall with a slot, a holder for pyrophoric material operating in said 125 130

slot, spring means for actuating the holder arranged wholly beyond the casing, a lever connected to the holder and pivotally supported on the casing, the upper and lower walls of said casing being formed in transverse line with the first mentioned slot and adjacent the non-slotted side wall with elongated apertures, an abrading element adapt-

ed to be passed thru said apertures with its ends normally seated therein, said element 10 being formed with an edge recess, and a screw threaded into the wall of the casing and seating in said recess.

In testimony whereof I affix my signature.

SAMUEL E. GUINN.
